ELECTRICAL APPARATUS

Tullio Tognola, Sidney, N. Y., assignor to Bendix Aviation Corporation, New York, N. Y., a corporation of Delaware

Application June 9, 1949, Serial No. 98,093

20 Claims. (Cl. 123—169)

1

This invention relates to electrical apparatus and more particularly to devices adapted for use in creating electrical spark discharges between spaced electrical conductors.

One of the objects of the present invention is to provide a novel spark gap construction whereby a high-energy spark discharge may be created across a relatively wide gap at relatively low voltage.

Another object of the invention is to provide a novelly constructed spark plug for a combustion engine or the like whereby ignition of a combustible charge may be obtained.

A further object is to provide a spark plug which will fire under adverse conditions far worse than those which would cause certain failure of operation in known types of spark plugs for the same purpose.

Another object is to provide a spark plug which will fire or spark at very low voltages so that the mechanical construction of the plug may be greatly simplified without danger of failure in operation due to flash overs and the like.

Still another object is to provide a device having a novel spark gap construction which inherently functions to prevent any serious fouling of even a very short gap and hence to prevent short circuiting of the gap and consequent failure of operation.

A still further object is to provide a spark discharge device embodying novel means for initiating a spark discharge from a source, the voltage of which is considerably below the normal breakdown or spark-over voltage of the gap.

Another object is to provide a novel spark plug for combustion engines which is so constructed as to substantially eliminate all danger of pre-ignition as a result of overheating of the spark plug parts exposed to the combustion chamber of the engine.

The above and further objects and novel features of the invention will more fully appear from the following detail description when the same is read in connection with the accompanying drawings. It is to be expressly understood, however, that the drawings are not intended to define the limits of the invention, reference for this latter purpose being had primarily to the appended claims.

In the drawings, wherein like reference characters refer to like parts throughout the several views,

Fig. 1 is a sectional side elevation view showing one form of device embodying the present invention;

2

Fig. 2 is a bottom view of the device of Fig. 1; Figs. 3 and 4 are sectional side elevation views similar to Fig. 1, with parts broken away, showing other forms of spark gap construction embodying the invention; and

Fig. 5 is a bottom view of the device of Fig. 4.

In the embodiments illustrated in the drawing, by way of example, the present invention is shown as being embodied in devices known commercially as spark plugs, said devices being adapted for use in igniting a combustible charge in the combustion chamber of an engine. As shown in Fig. 1, said device comprises a tubular metallic shell 10 adapted for threaded engagement with an opening in the cylinder of an internal combustion engine or in the wall of the combustion chamber of a jet-type engine or the like. In jet type engines the threads on the shell may be replaced by a mounting flange or other suitable supporting means. At the lower or inner end of shell 10 is an internal flange 11 which forms a shoulder to support and position the internal assembly of the plug. Seated on said shoulder and having electrical engagement with shell 10 is a ring electrode 12 which may be made of tungsten, nickel alloy or other suitable electrically conductive material. This electrode preferably has a sliding fit within the bore of shell 10 to thereby center the same within the shell. The engaging surfaces of ring 12 and shell 10 may be silver soldered or otherwise suitably joined together to insure good electrical contact and a high rate of heat dissipation from the electrode.

The center assembly within shell 10 comprises a central metallic rod 14 which may be recessed and filled with copper 15 or other suitable metal having high heat conductivity. The outer end of rod 14 is provided with an external flange 16, the upper face of which is in approximately the

same plane as the corresponding face of flange 11. Seated on flange 16 is an inner electrode ring 17 which has a sliding fit on rod 14 and has good electrical contact therewith. Ring 17 may, if desired, be secured to rod 14 in the same manner that ring 12 is secured in the shell. The outer diameter of electrode 17 is somewhat less than the inner diameter of ring electrode 12, thereby forming an annular spark gap 18, the width of which may vary appreciably, either

above or below the width of gaps found satisfactory in known types of spark plugs. Electrode 17 may also be made of tungsten, nickel alloy or other suitable conductive material which has been found satisfactory for use as spark plug

electrodes.

Fig. 1 is a sectional side elevation view showing one form of device embodying the present invention;

Novel means are provided for inducing an electrical spark discharge across gap 18 between the adjacent surfaces of electrode rings 12 and 17. In the form shown said means is constituted by a high resistance or semi-conductive ring 19 having surface contact with the electrode rings and bridging the gap 18 at the inner edge thereof. Ring 19 thus constitutes a high resistance path between electrodes 17 and 12 which apparently functions in an advantageous manner to be presently more fully described. The materials from which ring 19 is made may be chosen from a variety of suitable substances, the best choice being somewhat dependent upon the ultimate operating conditions. Ring 19 should, it is believed, be so constituted that an initial surge of electrical energy from a discharging condenser or the like at a voltage below the normal spark-over voltage of the gap will flow from electrode 17 to electrode 12 along the lower surface or skin of resistor ring 19 adjacent the gap. This electrical action apparently results in the ionization of the medium within gap 18 and reduces its spark-over or break-down voltage to a value not greater than the voltage of the remaining charge on the condenser or other source. With the resistance of the gap thus reduced, the remaining charge stored in the condenser will be dissipated across the gap in the form of a high-energy, low-voltage, high-frequency spark discharge.

It is preferable that ring 19 be insulated from both the center electrode bar 14 and shell 10 to thereby avoid the passage of excessive current through the body of the ring or along a surface which is not exposed to the gap. To this end, the outer periphery of ring 19 may be engaged by a depending annular skirt 20 on an insulating spool 21, the center part of which completely fills a portion of the bore of shell 10 around rod 14 to position the latter within the shell. Preferably, skirt or flange 20 does not engage electrode 12 so that ring 19 may contact said electrode under pressure to insure good electrical and heat conductances. An annular skirt 22 at the upper end of insulator 21 serves as a pilot for a cylinder or sleeve 23 of copper or other suitable high heat conducting electrical conductor. Sleeve 23 has an internal shoulder 24 against which the upper end of hollow rod 14 is spun or rolled to form a bead 25, whereby said rod, rings 17 and 19, insulator 21, and sleeve 23 are rigidly secured together under pressure as a unit or sub-assembly which may be readily inserted into shell 10 for engagement with electrode ring 12 as heretofore described.

The above-described central sub-assembly, which is in effect a center electrode assembly, may be secured in shell 10 by a gland nut 26 which is threadedly received by the upper end of the shell. In order to insulate the electrically conductive parts of the center electrode assembly from the shell and hence from ground, an insulator 27 is interposed between nut 26 and the upper end of sleeve 23. Said insulator also has a depending skirt 28 for positioning the upper end of sleeve 23 and spacing it from the inner wall of shell 10. The annular space between insulators 21 and 27 around sleeve 23 is preferably filled with a closely packed powdered insulation 29, several kinds of which are available. For example, powdered aluminum oxide, clay, magnesium oxide or the like constitute suitable fillers, but other types of solid or powdered insulation may be employed. A type of filler which will serve to conduct heat from sleeve 23 to shell 10 is desirable. 75

Suitable longitudinal pressure may be applied to the center assembly by nut 26 which, when tightened, may be brazed or otherwise suitably locked to shell 10.

5 Nut 26 is tubular and has a pin or plug contact terminal 31 mounted centrally thereof by means of a well known type of glass-to-metal seal 32. The outer end of said nut is externally threaded and recessed for receiving the female part of a plug and socket connector, in a manner well known in the art, to effect electrical connection between the spark plug and a source of electrical energy (not shown). The inner end of pin 31 extends into and makes electrical contact with a socket 33. The upper or hollow end of the latter comprises a plurality of spring metal prongs which resiliently engage pin 31, and the lower or solid portion of the socket member has a tight fit in a metal sleeve 34 which in turn has a press fit in the bore of sleeve 23. The void spaces within the spark plug may be filled under vacuum with a suitable insulating compound, if desired, in a manner now well understood in the art.

20 25 From the above description it will be understood that electrical energy may be supplied from a high frequency or other source to the spark plug through terminal pin 31. From pin 31 the current flows through socket member 33, sleeves 30 34 and 23, and rod 14 to inner electrode ring 17. When voltage is applied, the initial surge of current is believed to flow through resistor 19 along or adjacent to the lower surface or skin of said resistor adjacent gap 18 and thence to ground through outer electrode ring 12 and shell 10. The gap 18 is thereupon ionized, and the remainder of the stored or available energy creates a spark across gap 18. Successive sparks may occur at different points along the gap and are effective to burn or drive out of the gap any accumulations of foreign matter which might otherwise foul the gap and create a permanent low resistance path between the gap surfaces, a condition known in the art as "fouling."

35 40 45 Some of the materials which may be suggested, by way of example, for use in making semi-conductive ring 19 comprise various fused or compressed mixtures of suitable insulators, such as sodium silicate, clay, titanium dioxide, zirconium oxide, urea formaldehyde resins, and/or aluminum oxide with finely divided electrical conductors such as silicon carbide, titanium carbide, nickel, boron carbide, graphite, iron or the like. The insulating materials act as binders in the suggested mixtures for the electrically conductive compound. Ring 19 should be so constituted as to withstand high temperatures and substantial pressures when heated to operating temperature. It must also possess the property of resistance to burning and erosion in the presence of high energy spark discharges across gap 18. Fused mixtures of silicon carbide, alumina and sodium silicate and of iron powder and alumina have proved quite satisfactory in some installations. 50 55 60 65 It may be desirable to concentrate the conductive materials near the surface of ring 19 adjacent the gap to insure against possible dissipation of the electrical energy through the semi-conductive body rather than along the surface or skin thereof. If the cross-section of the resistor is small, the resistance may be sufficiently high even though a relatively good conductor is employed. The choice of materials and detail structure or composition of the resistor are matters for some experiment in each par-

ticular type of installation, the same being dependent to some degree upon many factors such as the energy desired, operating conditions, gap size and the like. Satisfactory compositions for ring 19 are also somewhat dependent upon the capacity of the condenser from which electrical energy is supplied, the voltage employed, and other operating factors and conditions which differ in different installations.

In the embodiment of Fig. 3 the flanges 11 and 16 on shell 10 and center electrode rod 14, respectively, are extended into spark gap relation to thereby eliminate the necessity for the electrode rings 12 and 17. The resistor or semi-conductive ring which bridges the gap 18 is constituted by a ring 36 of insulating material, such as a ceramic, with a coating or surface 37 of suitable material having high electrical resistance. The coating may be fused or otherwise applied to the face thereof adjacent gap 18, such as by electrolysis. For example, the coating 37 may comprise a mixture of iron powder and alumina made into a paste with a liquid, such as water, oil, alcohol, or the like. A thin coating of this paste is painted onto the ceramic ring 36 and fired at temperatures between 2000° F. and 3000° F. A crocus-martis-clay mixture has also been found satisfactory for coating the ceramic ring. In this embodiment of the invention, there is little or no danger that a disproportionate amount of electrical energy will be dissipated through the resistor ring or coating, but the operating life may be shortened by the burning away of said coating.

The embodiment of Figs. 4 and 5 is similar to that of Fig. 3 except that the gap bridging ring is constituted by a ceramic ring 38 having one or more recesses in the face thereof each filled with a filler piece 39 of high resistance or semi-conductive material. The filler 39 may be pre-formed or compressed in the recess in powdered form and in either case it may be fused to the walls of the recess. As shown, four cylindrical pieces 39 are embedded in ring 38, each of which bridges the gap 18. In this form the surface contact of the gap electrodes 11 and 16 with the semi-conductive elements 39 is considerably less than in the other embodiments thereby providing further protection against dissipation of electrical energy through the body of the gap bridging ring, while providing ample conduction for some applications to insure sparking across gap 18.

There is thus provided a novel spark plug which is admirably adapted for use in reciprocating engines as well as in jet type engines, the same being capable of firing at relatively low voltage so that the structure may be greatly simplified as compared to known structures adapted for accomplishing the same results. The novel spark gap construction embodied in said plugs is such that either a small or a larger gap may be satisfactorily used without appreciable danger of fouling or failure to produce a spark having sufficient energy. Use of a spark plug of the type provided makes it possible to reduce the size and weight of other parts of an ignition system or the like while increasing the efficiency, spark energy and reliability. Likewise, provision can be made in the construction for greater and faster heat dissipation thereby reducing the danger of preignition. Because a high capacity source may be employed to fire the present spark plug the gap may be relatively small initially so that only a very substantial amount of erosion

will render the plug inoperative, thereby greatly increasing its effective operating life.

Although only a limited number of embodiments of the invention have been illustrated in the drawings and described in the foregoing specification it is to be expressly understood that the same is not limited thereto. For example, the various types of resistance elements shown for connecting the gap electrodes may be employed equally well in any of the embodiments. Other suitable known means may also be provided for effecting a connection between the center electrode assembly and the source of electrical energy and the ceramic elements 21 and 36 of Fig. 3 or elements 21 and 38 of Fig. 4 may be fused together or constituted by unitary insulators. Various other changes may also be made in the relative sizes, design and arrangement of the parts illustrated, as well as in the composition of the materials suggested, without departing from the spirit and scope of the invention as will now be apparent to those skilled in the art. For a definition of the limits of the invention reference is had primarily to the appended claims.

What is claimed is:

1. A spark plug comprising a tubular shell, an annular electrode seated on an internal shoulder in said shell, a center electrode assembly 30 within said shell comprising a metallic rod, an annular electrode surrounding said rod in spark gap relation with said first-named electrode, a resistor surrounding said rod in spaced relation thereto and bridging said gap in contact with both said electrodes, a metallic sleeve surrounding said rod in contact therewith and extending beyond the end thereof to form a well, and an insulating ring interposed between said resistor and said sleeve, said ring having axially extending skirts for spacing said resistor and sleeve from said shell, said second-named annular electrode, resistor, insulating ring and sleeve being rigidly secured between external abutments on said rod, a tubular nut threadedly received by said shell for applying pressure to said assembly to press said resistor against said first-named annular electrode, an insulating ring interposed between said nut and sleeve and having a skirt for spacing said sleeve from the shell, insulation means filling the space in said shell around said sleeve and between said rings, an electrical socket mounted in said well, and a pin contact extending through and insulated from said nut for engagement with said socket.

2. A spark plug comprising a metallic shell, a ground electrode adjacent one end of the shell, a center electrode assembly comprising tubular insulating means, a center electrode having a spindle and an enlarged head portion and a resistor element bodily separate from said insulating means and clamped between said insulating means and the upper surface of said head portion, a marginal portion of the lower face of said resistor element being seated on the upper surface of said ground electrode, and means for securing said assembly in said shell and holding said resistor element in firm engagement with the upper surface of said ground electrode, said head portion and ground electrode being in spark gap relation and said resistor element being in spaced relation to both said shell and spindle.

3. A spark plug as defined in claim 2 wherein the resistor element is in the form of a ring having appreciable thickness and completely covering the

annular spark gap between said head portion and the ground electrode.

4. A spark plug as defined in claim 2 wherein the resistor element is detached from the said insulating means and consists of a rigid mixture of finely divided electrically conductive material and insulating material.

5. A spark plug as defined in claim 2 wherein said resistance element has a sliding fit in and projects from a recess in said tubular insulating means.

6. A spark plug as defined in claim 2 wherein the center electrode comprises an electrode ring having at least a marginal portion thereof interposed between said resistance element and said head portion.

7. A spark plug as defined in claim 2 wherein said ground electrode is constituted by a ring mounted in said shell.

8. A spark plug as defined in claim 2 wherein said ground electrode is constituted by a ring mounted in said shell and said center electrode comprises an electrode ring having at least a marginal portion thereof interposed between said resistance element and said head portion in spark gap relation with said ground electrode ring.

9. An ignition spark plug comprising a tubular metallic shell, an annular ground electrode adjacent one end of said shell, a center electrode assembly within the shell comprising a metallic rod with a spindle portion and an enlarged head portion constituting a center electrode and forming an annular spark gap with said ground electrode, means for insulating said rod from said shell and resistor means bodily separate from said insulating means and having a marginal portion tightly clamped between said insulating means and said center electrode and another marginal portion seated on said ground electrode, and means for securing said assembly in said shell and pressing said resistor means against said ground electrode, said resistor means being in spaced relation to both said shell and spindle.

10. A spark plug as defined in claim 9 wherein the resistor is in the form of a ring having appreciable thickness and completely covering the spark gap at the inner edge thereof.

11. A spark plug as defined in claim 10 wherein the resistor ring is positioned by said insulating means in spaced relation to the inner wall of the shell and the external surface of said spindle.

12. A spark plug comprising a tubular shell, an annular ground electrode adjacent one end of said shell, a center electrode assembly adapted to be assembled independently of said shell and ground electrode and insertable within said shell after being assembled, said assembly comprising a metallic rod having a spindle and an enlarged head portion constituting an electrode in spark gap relation with said ground electrode, a resistor bridging the gap between said electrodes and having surface contact with the upper surfaces only of both said electrodes and a tubular insulator surrounding said spindle, said insulator and resistor being rigidly secured to said rod with the resistor in firm engagement with said head portion and in spaced relation to said shell and spindle, and a tubular nut threadedly received by said shell for applying pressure to said assembly to press said resistor against said ground electrode.

13. A spark plug as defined in claim 12 wherein the ground electrode is constituted by a ring mounted in said shell and said center electrode assembly includes an electrode ring having at

least a marginal portion thereof interposed between said resistor and said head portion in spark gap relation with said ground electrode ring.

14. A spark plug as defined in claim 12 including a plurality of circumferentially spaced resistors slidably extending into and projecting from recesses in said tubular insulator.

15. In a spark plug, two coplanar flat annular discs of different dimensions concentrically disposed and having a circular space of substantially uniform cross-section between them to provide a spark gap, electrically conductive supporting means for the smaller disc engaging said disc at its upper, lower and internal surfaces, electrically conductive supporting means for the larger disc engaging said disc at its upper, lower and external surfaces, and an electrically insulative member mechanically interconnecting the two supporting means and retaining them fixedly positioned with respect to each other.

16. A spark plug as in claim 15 in which the discs are of substantially equal thickness and are of different internal and external diameters.

17. A spark plug as in claim 15 in which the supporting means are shaped to provide a circular groove having tapering walls sloping inwardly towards the spark gap, whereby the gases to be ignited by the spark plug may have free access to the spark gap.

18. In a spark plug, two concentric annular discs having an annular space of substantially uniform radial thickness therebetween to provide a spark gap, means for supporting said discs including means engaging the inner disc at its upper, lower and internal surfaces and the outer disc at its upper, lower and external surfaces, said disc-engaging means including an electrically conductive element engaging said inner disc and an electrically conductive element engaging said outer disc, and means including electrically insulative means mechanically interconnecting said disc-supporting elements and retaining said elements in fixed position with respect to each other.

19. In a spark plug, two concentric annular electrodes having an annular space therebetween of substantially uniform radial thickness to provide a spark gap, the innermost of said electrodes comprising an annular disc, electrically conductive supporting means for said disc engaging the same at its upper, lower and internal surfaces, electrically conductive supporting means for the outermost of said electrodes, and means including electrically insulative means mechanically interconnecting the two electrode-supporting means and retaining them in fixed position with respect to each other.

20. In a spark plug, two concentric annular electrodes having an annular space therebetween of substantially uniform radial thickness to provide a spark gap, the innermost of said electrodes comprising an annular disc, electrically conductive supporting means for said disc engaging the same at its upper, lower and internal surfaces, electrically conductive means engaging the outermost of said electrodes at its lower and external surfaces, said last-named means including supporting means for said outermost electrode, and means including electrically insulative means mechanically interconnecting said electrode supporting means and retaining the same in fixed position with respect to each other.
